Application January 26, 1955, Serial No. 484,241

Claims priority, application Belgium January 30, 1954

6 Claims. (Cl. 40—106.45)

This invention pertains to an advertising device and, more particularly, to a device particularly adapted to advertise ball-point pens or the like.

An object of the invention is the provision of a cradle or other support for a ball or a sphere which is engaged by a vibration producing device in order to set the ball or sphere in rotary motion.

A further object of the invention is to make the vibration producing device invisible by means of a casing built around it so that only the upper part of the rotating ball or sphere is visible.

Another object of the invention lies in the provision of a light source within the casing in such a manner that only the ball or sphere is illuminated.

For a better understanding of the present invention together with other and further objects thereof, reference is had to the following description taken in connection with the accompanying drawings and its scope will be pointed out in the appended claims.

With reference to the drawings:

Figure 1 is an isometric view of the advertising device with the casing removed.

Figure 2 is a side view of the device with its casing in place, as it would appear in a display window.

Figure 3 is a side view partially in section showing a modified form of the invention.

Figure 4 is a side view partially in section showing a portion of the device shown in Figure 3.

Figure 5 is a view showing a fragmentary part of the device and showing a modification which can be used.

With reference to the drawing there is shown in Figures 1 and 2 a base 1 upon which a frame 2 is mounted in a vertical position. A horizontally disposed bar 3 is connected across the frame 2 and supports an electromagnetic coil 4. The frame 2 includes an upper cross-bar 5 to which is connected a ring or cradle 6 held suspended above the coil 4. The diameter of the ring 6 preferably is slightly smaller than the diameter of a ping-pong ball, and the ball or sphere 8, which preferably is a ping-pong ball, is adapted to rest in the ring 6 and thus be held in a relatively fixed position.

One end only of a thin plate 9 is connected to the cross-bar 5 by means of a screw 10, and the plate 9 is located between the cross-bar and the ring 6. The plate 9 is made of material which will vibrate under the influence of alternating magnetic flux established by connecting coil 4 to a source of alternating electric current, such as the ordinary 60 cycle A.C. house current.

An actuating finger 11, preferably rubber tipped, is affixed, as by soldering, to the portion of the thin plate 9 under the ring 6, and extends diagonally upward so that its tip will touch the bottom of a ball mounted on the ring. It is important that the point of contact of the finger 11 with the ball 8 be offset in relation to a vertical plane passing through the center of the ball 8 so that as the finger 11 vibrates the point thereof moves

2

substantially vertically acting against the ball 8, so that it will raise the ball and will also impart to it a slight rotary motion.

Energization of the coil 4 causes the sub-assembly comprised of the plate 9, and the finger 11 to vibrate, and also causes the ball 8 to vibrate slightly. As the ball vibrates up and down it also rotates due to the off-center contact of the finger 11 with the ball and the component of thrust applied tangentially of the surface of the ball.

10 A preferred method for mounting the plate 9 on the frame 2 is shown in Figure 1, and comprises a bracket connected to one of the legs of the frame 2. An eccentric 12 is connected to a shaft rotatably mounted on the bracket, and a thumb screw 13 is connected to the shaft. The end of the plate 9 on the other side of the mounting screw 10 from the vibrating end extends over and in contact with the eccentric 12. As the thumb screw 13 is rotated the amplitude of vibration of the plate 9, the finger 11 and the ball 8 may be controlled.

20 The entire operating and control mechanism may be mounted within a casing 14 and thus be invisible, as shown in Figure 2. When such a casing is used the ring 6 may be eliminated as the circular top edge 15 of the casing serves the same purpose. An electric light 16 mounted inside the casing 14 may be used to illuminate the ball 8 from below.

The lead wires 17 of coil 4 extend from an alternating current source outside of the device, through hole 18 in the casing 14, to the electromagnet 4.

30 The device of the present invention operates with a ball which is perfectly spherical, or it may be used with a ball which is not spherical, thereby to achieve psychological effects which cannot otherwise be obtained. Further, various designs may be printed on the surface of the ball, or the ball may be provided with raised or hollow spots.

Figure 3 shows another embodiment wherein the ball 8 rests on the top of a vertically mounted transparent tube 20 around the lower end 21 of which the electromagnet 22 is mounted. Flexible rings 23 are positioned between the tube 20 and the electromagnet. The tube 20 is made of material responsive to the electromagnetic field generated by the coil 22 and thus reciprocates up and down, thereby vibrating the ball 8. A casing 14' covers the electromagnet but leaves visible the ball and part of the vibrating rod 20. A lamp 24 is mounted directly under the hollow tube 20 in order to illuminate the underneath side of the ball 8.

In the variation shown in Figure 4 a plexiglass tube 20' is tightly encircled at the bottom by rubber rings 25 connected to a vibrating plate 26 which is vibrated by an electromagnet 27, somewhat similar to the structure shown in Figure 1. The electromagnet is energized to vibrate the plate 26 and the plate, through the rubber rings 25, vibrates the tube 20'.

As shown by Figure 5 the upper end 28 of the tubes 20 or 20' can have an uneven shape so that as the ball 8 falls back onto the tube after being vibrated into the air it will not fall in exactly the same position. Thus the ball will turn as it vibrates, producing a wide variety of motions. To best produce this motion the top of the tube 20 or 20' should be hollowed out or concave to receive and hold the ball and one side of this receptacle should be slightly higher than the other.

65 While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. In an advertising device having a base and a ball supported in a relatively fixed position on the base, means for rotating the ball while in said position comprising, in combination, an electromechanical vibrator mounted on said base, an element engaging at one point the underneath surface of said ball at a location offset from the vertical axis thereof, means connecting said vibrator and element, said element being mounted such that the ball engaging point on said element moves substantially vertically upon actuation of said vibrator for imparting vertical vibrations to said ball to toss said ball vertically of the base with a component of thrust tangentially of the surface of the ball, to cause said ball to rotate.

2. An advertising device as set forth in claim 1, further characterized by means connected to said electromechanical vibrator for varying the amplitude of vibration of said element.

3. In a self-illuminated advertising device having a base and ball supporting means mounted on said base for supporting a ball, the combination comprising, means for transmitting vibrations to said ball for imparting vertical thrust to the ball tending to toss said ball vertically of the supporting means and tangential thrust to cause said ball to rotate with respect to the supporting means while in the air above the same, a hidden light source, said ball supporting means also forming means for focusing a light beam from said light source on to the underneath surface of said ball to illuminate said underneath surface while said ball is in the air above the supporting means.

4. An advertising device comprising, in combination, a base, a frame mounted on said base and having a cross-bar, an electromagnetic coil mounted on said cross-bar and within said frame, a vibratory plate mounted on said

frame and having a free end in the electromagnetic field established by said coil, a ring mounted on said base and located above said vibratory plate for suspending a ball therein, and a finger connected to said vibratory plate for engaging the underneath side of the ball suspended in said ring to cause said ball to vibrate.

5. An advertising device as set forth in claim 4, further characterized by said vibratory plate having a second free end, eccentric means mounted on said frame and in engagement with the said second free end of said vibratory plate, means for turning said eccentric with respect to said vibratory plate to vary the force therebetween thereby to vary the amplitude of vibration of the other free end of said vibratory plate.

6. In an advertising device having a base, and ball supporting means mounted stationary on said base for freely supporting a ball, the combination comprising, an electromechanical vibrator mounted on said base, a finger mounted independently of said supporting means for engagement with the underneath surface of said ball at a point offset from the vertical axis thereof, said finger being carried by said vibrator for imparting vertical vibrations to the ball to toss said ball vertically of the supporting means with a component of thrust tangentially of the surface of the ball, to cause said ball to rotate with respect to said ball supporting means while in the air above the same.
